ATTORNEY.

UNITED STATES PATENT OFFICE.

ALEXANDER McDougall, of Duluth, Minnesota.

SHIP CONSTRUCTION.

1,257,621.

Specification of Letters Patent. Patented Feb. 26, 1918.

Application filed October 9, 1916. Serial No. 124,525.

To all whom it may concern:

Be it known that I, ALEXANDER McDougall, a citizen of the United States, residing at Duluth, in the county of St. Louis and State of Minnesota, have invented certain new and useful Improvements in Ship Constructions; of which the following is a specification, reference being had therein to the accompanying drawing.

10 My present invention consists of certain improvements in ship construction and relates particularly to the framing of steel ships and is especially applicable to such in which it is desired to form a double bottom 15 and having a plurality of compartments between the bottoms for use as water ballast tanks, for carrying liquid fuel or the like.

For a ready comprehension of the objects of the invention and a comparison with the ordinary practice in such construction, I will relate that the bottom frames of the ordinary steel ship extend from the center keelson to within a short distance of each side, that is, that portion of the frame composed of a single piece of metal. The individual pieces of side frames terminate a short distance above and beyond the ends of the bottom frames and the space thus formed intermediate these adjacent ends is spanned and coöperatively unite the lower ends of the side frames with the bottom frames by suitable bracket plates, the outer edges of which are rounded, forming the bilge of the ship. This form of corner or 35 bilge also provides means for an angle plate running fore and aft and terminating the compartments intermediate the double bottoms and to which the upper bottom or tank top is attached by suitable angles.

40 These bracket plates are riveted to the side frame and fastened to the tank top by angle irons.

They are also faced with angle irons along their inner edges and to which the inner bilge 45 plates are fastened.

It is evident that this form of corner or bilge necessitates very expensive fabricated construction and deprives the hold of the vessel of considerable carrying capacity, with 50 the only possible advantage, which to a large degree is theoretical, of providing a rounded bilge.

This rounded bilge is found in many cases to have other disadvantages in that it permits of abnormal rolling of a ship thus con-

structed and to overcome which, bilge-keels are fixed thereupon in an attempt to restore the stability afforded by the corner that would have been formed by the direct meeting of the floor frames with the side frames 60 as disclosed in my novel plan of framing.

The inner bottom or tank frames, as they are called, are made by vertical plates full depth of the tank riveted to upper and lower floor beams and where not acting as division 65 walls for the various compartments into which the tank is divided, are provided with numerous manholes through which workmen may pass in building, repairing or painting, as the case may be. 70

The tank or double bottom is usually divided into six or more compartments by the center keelson or bulkhead which extends the full length of the ship and two or more thwartship bulkheads the full width of the 75 ship. These may again be subdivided into smaller compartments by vertical plates and angles, all of which require additional holes and entrance means for workmen and very obviously complicate the construction. It 80 has been proven repeatedly and beyond question that this complicated form of cellular construction of ship's bottom is very hard to maintain in proper shape and repair and its inaccessibility causes neglect and unseaworthy conditions, besides the great initial expense. 85

The object of this invention is to materially lessen the cost of construction and quantity of material necessary in an improved form of hull having all the advantages, number of compartments, et cetera, of the ordinary ship and a form of construction much more easy of access for repairs, and the like, with the added advantage of 95 the direct use of a much larger proportion of mill-run material. 90

Another object is to provide a form of ship construction and arrangement of framing admirably adapted to the standardization of ships' hulls which is a phase of the ship building industry rapidly becoming a necessity. 100

Other objects and advantages of my novel form of framing will appear in the further 105 description of the invention and particularly pointed out in the claims.

In the accompanying drawings forming part of this application and in which like reference characters indicate like parts. 110

Figure 1 is an elevation of one of my improved frames, as it would appear in the cross sectional view of a ship's hull, at one of the center stanchions, and

5 Fig. 2 is a longitudinal vertical section taken on the line A—B Fig. 1, looking toward the center stanchions.

The bottom truss is formed of two separate units of fabricated construction each 10 consisting of a straight horizontal channel floor bar, 1 and a second similar though preferably heavier bottom bar 2, spaced the requisite distance below the bar 1 to form 15 desired depth of tank. This bottom bar inclines slightly upwardly toward the side of the frame just sufficient to form the necessary deadrise and is united to the floor bar 1, at the inner end thereof, by means of a short vertical channel 3 with its back 20 tightly riveted to the backs of the channels 1 and 2 and half way between the center of the frame and each side is another vertical channel 4 fastened in the same manner. Upon each side of the frame and at the extreme outer ends, the two channels are 25 united by the side frame 5 which is also a channel bar and riveted back to back thereto, thus forming a practically square corner though slightly obtuse due to the upward inclination of the channels 2. The side channels 5 extend upwardly and similarly unite the two outer ends of channels 6 and 7 which together with their cross braces 8 and central connection constitute the 30 upper deck truss which is similar to the bottom truss except that it is inverted, the beam 7 inclining downward toward the sides from the center to form the necessary camber. This forms the upper corners of 35 the frame practically square except for the inclination of the beam 7 which makes the angle of the corners slightly obtuse and very similar to those of the lower corners.

40 The deck channel 7 may be bent sharply at its center and the inclination toward the sides perfectly straight or it may be arched gradually as preferred.

I have shown center channel stanchions 45 9 as occurring intermediate the hatch openings in the upper deck and the opposite ends of which are securely united to the bottom truss of each respective frame.

50 Between the abutting ends of the two halves of the bottom truss extends longitudinally the hull the central bulkhead plate 10 to which plate the fore and aft angles of the channels 3 are securely riveted, thus forming a secure and strong bond in the center of the truss.

55 It is evident that a bulkhead plate, not shown, may be riveted to the backs of the channels 1 and 2 between the center bulkhead and the sides wherever desired to form a thwartship bulkhead and when it is 60 desired to subdivide these compartments,

athwartships, bulkhead plates 11 may be secured to the vertical channel braces 4 and the space from the center to the sides is divided into two equal parts.

Upon the floor plates which extend to 70 the sides of the hull, longitudinally extending angle bars 12 are used at the junction of the side frames with the floor channels 1 and behind which against the skin of the ship, between the side frames a suitable 75 waterproof cement filling is used as indicated at 13.

While I have shown stanchions 9 as occurring midway between the hatches and extending to the tank top or floor of the 80 hull, I wish it to be understood that these may be dispensed with, if desired, and the center of the top truss, that is, the two channels 6 and 7 be united by short pieces of channel similar to the pieces 8 and two 85 or more of the deck beams 7 may be thus reinforced and form a coöperative part of an additional upper deck truss, for properly strengthening and supporting the deck of the ship, and as may be considered 90 necessary abreast the hatches.

It is evident that in this form of truss or ship's girder, made of channel iron, I have provided great strength with simplicity of construction and in the case of the bottom 95 girder, one whose compartments are accessible in all directions and requiring the least number of manholes or openings for construction or maintenance.

Any desired arrangement of plating 100 forming the skin of the ship or the tank top may be employed.

Having thus described my invention what I claim as new and desire to secure by Letters Patent, is:

1. A ship's thwartship frame composed 105 wholly of channel bars, the backs of which are riveted to each other, the lower horizontal portion of the frame consisting of two oppositely disposed sections, each section comprising an upper straight horizontal channel bar and a lower inclined straight channel bar spaced apart and united by short vertical channel bars, the upper horizontal portion of the frame consisting of a lower 110 straight channel bar extending from side to side of the frame and two inclined channel bars placed end to end, spaced from and united with the lower straight channel bar and forming the upper member of said portion of the frame, and single vertical side members uniting the ends of said lower and upper portions, substantially as described.

2. A thwartship frame for ships' hulls 115 comprising a truss forming the bottom of the frame, composed of a plurality of straight horizontal members, two straight opposed members upwardly inclined from the center of the bottom of the frame and spaced apart from and below the first men-

tioned members, a plurality of short vertical members uniting said spaced members and forming a rigid truss thereby, a similarly constructed inverted truss forming the top 5 of the frame and straight vertical side members uniting the ends of the upper and lower trusses.

3. The combination with a ship's hull substantially rectangular in cross-section, of 10 thwartship frames comprising a lower truss and an upper truss each having straight horizontal inner chords and straight outer chords converging toward the inner chords from the center of the frame, single vertical members uniting the ends of the trusses and forming the sides of the hull, a single member uniting the centers of the trusses and short vertical members uniting the chords of each truss intermediate of the center and 15 the ends thereof, substantially as described.

4. The combination with a ship's hull substantially rectangular in cross-section and having a plurality of single thwartship upper deck frames intermediate of the hatches 20 thereof, of one of said frames having a thwartship beam spaced therefrom and below the same, a single member centrally uniting said spaced beams and extending to the lower portion of the hull and two 25 short vertical members uniting the spaced

beams intermediate of the center and the ends thereof.

5. The combination with a ship's hull substantially rectangular in cross-section, the framing of which is composed chiefly of 35 channel bars, and having hatches therein, of a plurality of fore and aft spaced channel bars intermediate of the hatches and upon which the upper deck is supported, a channel bar spaced below and parallel with 40 one of the first mentioned channel bars and fixed thereto, channel bars spaced apart vertically and attached to each other forming the lower portion of the hull frame, a central single channel bar stanchion intermediate of each pair of hatches and attached at one end with its back against the backs of the two lower vertically spaced channel bars and at its opposite end with its back 45 against the backs of the two upper vertically spaced channel bars and single channel bars at each side of the frame uniting the ends of the upper and lower portions thereof, substantially as described.

In testimony whereof I hereunto affix my 50 signature in the presence of two witnesses.

ALEXANDER McDougall.
